SHINGLE STRIP

Herbert G. Goslin, Battle Creek, Mich., assignor,
by mesne assignments, to The Patent and Li-
censing Corporation, New York, N. Y., a cor-
poration of Massachusetts

Application June 22, 1935, Serial No. 27,863

2 Claims. (Cl. 108—7)

This invention relates to an improvement in roofing elements and is concerned particularly with an improved form of shingle strip of flexible base material such as the well known type of composition asphalt roofing.

Because of the flexible nature of asphalt composition roofing prepared from a base of fibrous felt, saturated and coated with asphalt, and surfaced with mineral grit, shingle strips cut from 10 such prepared material and laid in overlapping courses require certain minimum amounts of so-called headlap for a given exposure of each strip to the weather, the exposure itself being also limited, in order to insure adequate protection 15 against leakage. Thus, for example, the well known form of square butt strip shingle when made in a width of 10" cannot be exposed more than 4" to the weather without reducing the headlap to less than 2" and thereby jeopardizing the safety of the roof. Such strips, with a 20 4" exposure and 2" headlap require 250 square feet of base material to cover 100 square feet of roof or area. Even where such strips are made on a heavier felt base permitting a 5" exposure 25 with a 2" headlap, this form of strip requires 240 square feet of material to cover 100 square feet in area.

A substantial saving of material, for comparable exposure and headlap is obtained when 30 using shingle strips of the type shown in patent to Cumfer No. 1,604,339 wherein the strips are provided with semi-hexagonal tabs spaced from one another by intervening recesses which are complementary in size and shape to the tabs. 35 Shingle strips such as shown in the Cumfer patent when designed to be laid with a 4" exposure and 2" headlap require only 200 square feet of material per square as contrasted with 250 square feet per square in the case of the 40 square butt strips of the same exposure and headlap. In such case, however, there is a substantial part of the roof area that is covered only by a single thickness of material. The hexagonal type of shingle strip has been manufactured in 45 forms which provide a so-called "double coverage", that is to say, when they are laid, there is no part of the roof area which is covered by less than two layers of material. In such forms of the hexagonal strip shingle, this double coverage construction requires not less than 250 square feet of material to cover 100 square feet of surface.

The principal object of my invention is to provide a form of shingle strip which can be laid 50 so as to furnish the so-called "double coverage"

effect and yet require a considerable smaller amount of material than in the case of double coverage hexagonal shingle strips heretofore employed. In terms of specific figures it may be stated that a shingle strip constructed according 5 to my invention and dimensioned so as to be laid with a 4" exposure to the weather the double coverage effect can be obtained with the use of 225 square feet of material as contrasted with 250 square feet of material in the case of the common 10 form of hexagonal strip shingle having the same exposure. Thus, the saving in material attained by my invention amounts to 10% of the amount 15 that would ordinarily be required to give the same effect.

My invention possesses other objects and advantages, some of which, with the foregoing, will appear from the detailed description of the invention which is illustrated in the accompanying drawing. It is to be understood that the invention is not limited to the specific embodiment 20 shown in the drawing and described herein, and that various forms of the invention may be adopted within the scope of the claims.

In the drawing:

Figure 1 shows one of the shingle strips constructed in accordance with my invention;

Fig. 2 shows the manner in which the strips of Fig. 1 may be severed from a sheet of base material; and

Fig. 3 illustrates a section of roofing or other area covered with overlapping courses of the strips shown in Fig. 1.

As already indicated, the shingle strips of my invention are of the flexible type, and more particularly are severed from a base or parent sheet of prepared roofing as commonly made by saturated bibulous felt, coating the saturated felt base on one or both surfaces with weather protecting coating such as high melting point 40 asphalt, and surfacing the coating at least on the face to be exposed, with crushed mineral grit such as slate or other comminuted material.

Referring in detail to the drawing, the shingle strip of my invention comprises a body portion 45 generally indicated by the numeral 10, the end edges 11 and 12 thereof extending at an angle of approximately 45° to the longitudinal axis of the strip and being parallel to one another. At its lower boundary the body portion is formed 50 with spaced tabs 13, 14, the tab 13 having the upper end of its outermost edge 15 spaced from the extremity 16 of the strip a distance equal in length to that of the butt edges 17 of the tabs, so as to provide a horizontal edge 18 at one end of 55

the lower boundary of the body portion. The space intervening between the tabs 13 and 14 is complementary in shape and equal in size to that of the tabs, being defined by the edges 19 and 20 of the tabs 13, 14, respectively, and by horizontal edge 21 at the lower boundary of the body portion, in horizontal alignment with and of length equal to the edge 18. It will be noted that the outermost lateral edge of the tab 14 forms a prolongation of the outermost edge 12 of the body at the corresponding end of the strip.

Along the upper boundary of the body portion are formed tabs or extensions which are so located and dimensioned in relation to the exposure tabs 13, 14 as to make possible the attainment of the principal objects of the invention hereinabove set forth. Accordingly, said upper boundary is provided with tabs or extensions 30, 31, the tab 30 being positioned so as to lie in substantial transverse alignment with the space intervening between the tabs 13 and 14 on the lower boundary of the strip. The tab 31, as will be noted, is located at the end of the strip, having its outermost lateral edge 32 formed as a prolongation of the outermost edge 12 of the body portion just as is the outermost edge 22 of the tab 14. Between the tabs 30 and 31 there is an intervening space 33 which is complementary in size and shape to the tab 30, being defined by the inner edges 34, 35 of the tabs 30, 31, respectively, and by a horizontal edge 36 at the upper boundary of the body portion. The outer edge 37 of the tab 30 is preferably parallel to the inner edge 35 of the tab 31, both being preferably parallel to the lateral edges 11, 12 of the strip. The lower extremity of the edge 37 is spaced from the upper extremity of the edge 11 of the strip a distance equal to the upper edge 38 of the tab 31, and said spacing is defined by the edge 37 and the horizontal edge 40, in alignment with the edge 36, at the upper boundary of the body portion.

In the preferred form of the strip as illustrated, the depth or transverse dimension of the tabs 30, 31, measured at right angles to the longitudinal axis of the strip is preferably approximately one-half that of the exposure tabs 13, 14; while the transverse dimension of the body portion itself, measured from the line of the edges 36, 40 to the line of the edges 18, 21, is equal to the sum of the transverse dimension of the tabs 13 and 30 (or 14 and 31).

In Fig. 2 there is illustrated the method by which the shingle strips constructed according to my invention may be cut without waste from a continuous web or sheet of prepared composition material. As there illustrated the successive strips are severed from the web, on the bias, by means of a succession of broken lines of severance, alternate ones of which, as designated by the numerals 50, 52 produce the above described formation of the tabs 13, 14 and intervening spaces of two adjacent strips in the sheet, while the intervening lines of severance, as designated by the numerals 51, 53 produce the formation above described at the upper ends of one of said strips, and complementarily, for the succeeding strip in the sheet.

In Fig. 3 is shown the manner in which the strips are laid in successive overlying courses. It will be noted that these strips are laid in the usual manner with the tabs 13, 14 exposed to the weather, the butt edges 17 of the tabs overlying and registering with the horizontal edges

18, 21 of the strips in the next underlying course. It will be observed from the contour of the overlapped portion of the strips shown at the upper edge of Fig. 3 in dotted lines, that the extensions 30, 31 are so arranged and located that at no place throughout the covering is there any area of the surface which is covered by less than two thicknesses of material.

I am aware that prior to my invention shingle strips have been made with exposure tabs of semi-hexagonal form and with tabs or extensions along the upper edge of the strips, such as shown for example in Letters Patents No. 1,473,919 to Abraham, No. 1,445,161 to Ott and No. 1,773,352 to Finley. I believe however that I am the first to construct shingle strips of such character which can be laid to give the double coverage effect with as little as 225 square feet of material and yet can be cut without waste from the parent sheet.

It will be understood that various modifications may be made in the form of the strip without departing from the principle of the invention. Thus, the angle of inclination of the side edges 15, 19, 20, 22 of the tabs 13, 14 may be varied one way or the other or these edges may take the form of slight curves or other contour without altering the effect of double coverage or affecting the ability to sever the strips from the sheet in the manner shown in Fig. 2, since the severance of the lines such as 50, 52 is quite independent of the severance along lines 51, 53.

What I claim is:—

1. A roofing element comprising a body portion having a plurality of exposure tabs extending from the lower boundary of said body portion and spaced from one another by spaces complementary in size and shape to said tabs a lateral edge of one of said tabs being formed as a prolongation of one lateral edge of said body portion, an extension formed at one end of the upper boundary of said body portion, said extension being substantially in the form of a parallelogram having one of its sides formed as a prolongation of said one lateral edge of said body portion, another extension formed along the upper boundary of said body portion and spaced from said first named extension by a space complementary in size and shape to the said second extension, said second extension being spaced from the opposite lateral edge of said body portion by a space corresponding in size and shape to that of said first named extension, the spacing of said extensions being such that they are offset with respect to the tabs longitudinally of the element a distance sufficient to lie substantially in transverse alignment with the spaces on said lower boundary.

2. A roofing element comprising a body portion having a plurality of exposure tabs of semi-hexagonal configuration, extending from the lower boundary of said body portion and spaced from one another by spaces complementary in size and shape to said tabs, a plurality of extensions on the upper boundary of said body portion and of equal number but of substantially lesser transverse extent than the tabs and offset with respect to the tabs longitudinally of the element a distance sufficient to lie substantially in transverse alignment with the spaces on said lower boundary, an edge of one of said tabs and an edge of one of said extensions being formed as continuations of one end edge of said body portion.

HERBERT G. GOSLIN.
